WINDOW BURGLAR ALARM

Carl M. Bartram, Chico, Calif.

Application December 7, 1948, Serial No. 63,865

1 Claim. (Cl. 116—87)

1

This invention relates to burglar alarm devices for windows; my principal object being to provide a device of this character adapted to be mounted in connection with an ordinary residential double-hung sash window, and which when properly set will give an audible alarm whenever the lower sash is raised or the upper sash is lowered.

Another object is to provide a device for the purpose in which the alarm given is of such a nature that its functioning will tend to frighten away a would-be intruder so that he will desist in his attempt to enter.

A further object is to provide an alarm device which may be set at any desired adjustable point in the height of the window, and which will permit either the upper or the lower sash to be initially opened a predetermined amount, as is desirable for ventilation, without interfering with the functioning of the device should an attempt be made to open either sash further.

A further object of the invention is to provide a practical and reliable burglar alarm for windows, and one which will be exceedingly effective for the purpose for which it is designed.

These objects are accomplished by means of such structure and relative arrangement of parts as will fully appear by a perusal of the following specification and claim.

In the drawings:

Fig. 1 is a fragmentary sectional elevational outline of a double-sash window showing the burglar alarm device mounted in connection therewith and in a set or cocked position.

Fig. 2 is a similar view showing the device tripped to give the alarm.

Fig. 3 is a back view of the device, detached.

Fig. 4 is an inner edge elevation of the same.

Referring now more particularly to the characters of reference on the drawings, the device comprises a rectangular, relatively shallow housing 1, the front of which is closed by a removable cover plate 2, which is left off in Figs. 1 and 2 to show the interior mechanism.

A rigid flange 3 projects from the rear of the housing at its outer side, and a similar flange 4, parallel to the flange 3, is disposed intermediate the side edges of the housing. The flange 4 is rigid with a lateral base bar 5 slidably guided on the back of the housing for lateral movement, and engaged by a spring urged lever 6 which is pivoted on the back of the housing below the bar and projects above the housing for manipulation by the operator.

The flanges are arranged to project into the

2

window casing groove for the lower sash 7; the flange 3 then engaging the parting bead 8, and the flange 4 engaging the inner framing member of the casing. To mount the housing in place, the flange 4 is initially retracted somewhat by a lever movement to enable the flanges to fit the respective casing members, so that when the lever is released the housing is frictionally held in place and may be easily moved up or down the sash groove to whatever position may be desired, and according to the extent the lower sash is to be open, without actuation of the alarm.

The alarm mechanism of the device is disposed within the housing and is arranged as follows:

Fixed in the housing at its inner side wall 10 is an anvil 11 adapted to support a percussion cap 12, which is placed on said anvil through an opening 13 in the sidewall 10; the opening 13 being closed by a slide gate 14.

A hammer 15 to engage the cap is pivoted, as at 16, in the housing, a spring 17 being applied to the hammer and tending to lower the same sharply.

A finger 18 extends from the hammer substantially radial with the pivot 16, and is normally engaged by a shoulder 19 formed in a holding bar 20 which is pivoted, as at 21, in the housing and is disposed with an upward slope to the inner wall 10 of said housing.

A spring 22 acting on said bar tends to maintain the shoulder in engagement with the finger 18.

A horizontal trip lever 23 is pivoted, intermediate its ends as at 24, in the housing below the lower end of the bar 20, and is formed with an upstanding lug 25 at its laterally inner end, while a guided arm 26 upstands from the opposite end of the lever.

A trigger plunger 27 extends from the housing into the path of opening movement of the top of the lower sash 7, and is guided for vertical movement in a sleeve 28 in the housing, the plunger being positioned to engage the under side of the lever 23 adjacent the lug 25, or at a point laterally outward of the lever pivot 24.

Another horizontal trigger member 29, yieldably advanced by a spring 30, projects from the outer side of the housing and is provided on its outer end with a cushion head 31 adapted to frictionally engage the adjacent side frame of the upper sash 32. The member 29 is disposed above the bar 20 and is slidably in a sleeve 33 pivoted in the housing, as at 34, so that said member may

swing up and down in a vertical plane, the outer side wall of the housing being vertically slotted to allow of such movement. At its inner end the sleeve is provided with a depending lug 35 positioned to engage the adjacent or inner end of the bar 20.

It will thus be seen that if the lower sash is raised or opened until it engages and lifts the plunger 27, the bar 20 will be swung up about its pivot 21. This releases the hammer finger 18, and the hammer will drop, urged by the spring 17, and said hammer will detonate the cap 12, giving an audible alarm and one which will simulate the shooting of a firearm. Similarly, if the member 29 is swung up by a slight upward movement of the upper sash 32, the lug 35 will be depressed and the bar 20 will be swung in a hammer releasing direction. If the sash 32 is lowered or opened, the member 29 will be swung down, engaging and depressing the arm 26, and swinging the lever 23 in the same direction, and with the same result, as when said lever is thus moved by the plunger 27.

Once the hammer is released and the alarm given, the hammer is reset by merely lifting up on a finger 36, which is rigid with, and projects from, said hammer through a slot 37 in the housing. The door 14 is lowered, exposing the anvil for the removal of the detonated cap and the insertion of a fresh one.

Since the holding or clamping means of the housing enables the same to be readily mounted at any desired position in the height of the window casing, the lower sash may be opened to any desired extent for ventilation before the alarm will be actuated. Similarly, the upper sash may be opened to any desired extent, if this is done before the device is mounted in place.

From the foregoing description it will be readily seen that there has been produced such a device as substantially fulfills the objects of the invention, as set forth herein.

While this specification sets forth in detail the present and preferred construction of the device, still in practice such deviations from such detail may be resorted to as do not form a departure from the spirit of the invention, as defined by the appended claim.

Having thus described the invention, the following is claimed as new and useful, and upon which Letters Patent are desired:

In a burglar alarm device, for a double-hung sash window, having a housing adapted to be supported from the casing of the window inwardly of the upper sash and above the lower sash, a spring-urged cap-detonating hammer mounted in the housing, and a detonating element in the path of and cooperating with the hammer element; a holding bar pivoted intermediate its ends in the housing above the hammer, means between the hammer and bar normally holding the hammer cocked but arranged so that the hammer will be released upon upward movement of one end of the bar and corresponding downward movement of the other end thereof, means including a lever functioning upon upward movement of the lower sash to move said one end of the bar upwardly, a spring-advanced trigger member projecting from the housing transversely of the upper sash to frictionally engage the same, means mounting the trigger member for up and down swinging movement, means between the trigger member and lever to cause the latter to be moved in a direction to move said one end of the bar upwardly upon downward swinging movement of the trigger member, and means between the trigger member and bar to move said one end of the bar upwardly upon upward swinging movement of said trigger member.

CARL M. BARTRAM.
